SODIUM VAPOR LAMP

John W. Marden, East Orange, N. J., assignor to
 Westinghouse Lamp Company, a corporation of
 Pennsylvania

Application July 29, 1933, Serial No. 682,753

9 Claims. (Cl. 176—122)

This invention relates to electric discharge devices and more particularly to devices of this character that are to be employed for illuminating purposes. In its more specific aspect the invention is directed to an alkali metal vapor lamp such as, for example, a sodium vapor lamp. This invention is an improvement over the lamp described by me in my patent application Serial No. 668,506, filed April 29, 1933 and assigned to the same assignee as the present invention.

In said application I have described an alkali metal vapor lamp comprising an elongated or tubular envelope having therein four anodes and a cathode. Also located within said envelope is an alkali metal vapor such as sodium. The anodes are so arranged that two of them are disposed near one end of the envelope and the other two are disposed near the other end of the envelope. One anode at one end is electrically connected to an anode at the other end. In like manner, the other anode at said first mentioned end is connected to the other anode at the second mentioned end.

The secondary of a low voltage transformer has its ends respectively connected to each pair of anodes and the midpoint thereof connected to the thermionic cathode. When one pair of anodes is positive with respect to the cathode, the current flow between the anodes and cathode is divided in two paths, one path being between one of the anodes of the pair and the cathode and the other path between the other anode of the pair and the cathode.

In the course of my experimentations with lamps of this character I have observed that temperature distribution is an important factor for efficient lamp operation. Temperature distribution is of prime importance because it is well known that the equilibrium vapor pressure of the alkali metal within the envelope is dependent upon the temperature of the envelope at the coolest portion thereof. Another factor that sometimes must be taken into consideration is blackening of the envelope adjacent the anodes. This, I believe, to be due to anode sputtering.

In order that any anode sputtering may be confined where it is least noticeable and so that I may properly fix the temperature distribution of an alkali metal lamp, I have developed the following invention.

Instead of dividing the current between the two anodes on each half cycle of the alternating current input, I prefer that substantially all of the current on each half cycle shall travel to a single anode. By this means, that portion of the

envelope adjacent the anodes may be kept at the proper temperature. In addition, the anodes may be located near the lower end of the envelope because that portion is generally covered by a suitable base or the light passing therethrough is in most cases not utilized.

Accordingly an object of my invention is to provide an improved alkali metal vapor lamp having improved electrical characteristics.

Another object of my invention is to dispose the anodes in an alkali metal vapor lamp that substantially all the discharge current will travel between the cathode and a single anode on one-half cycle of the alternating current source of potential connected thereto.

A still further object of my invention is to provide an alternating current alkali metal vapor lamp having its anodes located in the neck portion of the envelope thereof.

Other objects and advantages of my invention will become readily apparent from the following description and appended drawing wherein,

Figure 1 represents a cross-sectional view with some of the parts in elevation of my improved luminous discharge device; and

Figure 2 represents a cross-sectional view taken on line II—II in the direction of the arrows.

As illustrated, my invention comprises an alkali metal vapor lamp including an alkaline metal resisting vitreous envelope 9 having anodes 10 and 11 and a cathode 12 therein. An alkali metal such as sodium, rubidium, caesium or the like together with a small proportion of neon, is also contained in said envelope. The major portion 13 of the envelope is substantially spherical in shape and has a cylindrical neck portion 14 integral therewith. Fusedly sealed to the lower end of said neck 14 is a reentrant tube 15 having a press 16 at the upper end thereof.

Hermetically sealed in said press are a plurality of leading-in conductors 17, 18, 19 and 20 extending exteriorly and interiorly of said envelope, with the portions thereof extending interiorly thereof being rigid supporting members. Secured to the upper ends of the conductors 17 and 18 is the cathode 12 consisting of a coiled tungsten filament around which is located a nickel coiled filament with calcium, barium or strontium oxide or carbonates generally employed for electron emission purposes. Inverted L-shaped rods 21 and 22 of molybdenum or the like are secured respectively at their short arms 21' and 22' to the conductors 19 and 20. These short arms extend towards each other and are spaced an appropriate distance from the ends 55

and act as auxiliary or starting anodes so that a discharge may be effectively initiated within said envelope at the voltages employed.

The long arms of said inverted L-shaped rods 5 extend towards the lower end of the envelope and terminate below the press 16 and adjacent the lower portion of the interior of said envelope. Secured by welding to the lower ends of said arms 21 and 22 respectively are the main 10 anodes 10 and 11. Each of said anodes consists of an annular band or ribbon of a refractory metal such as molybdenum or the like. The anodes 21 and 22 are concentric with the stem 15 and are in substantially the same horizontal 15 plane and spaced from each other.

Surrounding the press and a major portion of said stem 15 is a nickel shield 23 to protect the press, seals and stem from bombardment. A base 24 is secured to the lower portion of said 20 envelope and the exterior portions of the leading-in conductors are appropriately secured to the usual contact pins carried by said base.

It is well known that when one body is contiguous with another body there is formed a 25 heat-conducting path and that if the temperature of one body is elevated above that of the other, the temperature of the first mentioned body will be lowered and that of the other will be increased because of heat transferred from 30 the body of elevated temperature to that of lower temperature. By so disposing the anodes 21 and 22 in the neck of the envelope, the temperature of the envelope at the lower portion thereof may be of such a magnitude that the 35 heat variations thereof, due to basing, are compensated for. This result is further dependent on having substantially all of the discharge current of the half cycles of the alternating current pass directly between the respective anodes 40 10 and 11 and the cathode 12.

The anodes 10 and 11 are located a sufficient depth in the neck of the envelope and the base 24 is of such a depth that the base surrounds that portion of the envelope which may become 45 blackened because of anode sputtering. The interior rigid portion of the leading-in conductors are provided with insulating sleeves 26 composed of alundum or the like. These sleeves surround the leading-in and supporting conductors and 50 protect said conductors from bombardment and consequent sputtering.

To augment the efficiency of the lamp, the same is provided with a double walled chamber 25 which may be either filled with a gas having 55 a low heat conductivity characteristic, or may be highly evacuated. The chamber 25, together with an insulating asbestos packing 27, surrounds said lamp and prevents air circulation around the exterior of the envelope thereof.

Although my invention is susceptible to numerous modifications, it is not to be limited to the exact construction herein specified but is to be limited only by the prior art.

What is claimed is:

1. An electric device comprising an envelope having a reentrant stem terminating in a press, an alkali metal, a thermionic cathode and a plurality of main anodes in said envelope, all of said anodes surrounding said stem, a plurality 70 of supporting conductors sealed in said press and electrically connected to said cathode and anodes.

2. An alkali metal vapor lamp comprising an envelope having a press, an alkali metal, a thermionically active cathode, a starting anode and 75 a plurality of main anodes therein, said main

anodes encircling said stem, all of said main anodes being located at one end of said envelope.

3. An alkali metal vapor lamp comprising an envelope, sodium, a plurality of main anodes, and a thermionically active cathode therein, said main anodes located at one end of said envelope, a base mounted on said envelope, said base encircling said main anodes and extending above the upper edge of said anodes. 5

4. An alkali metal vapor lamp comprising an envelope, sodium, a plurality of main anodes and a thermionically active cathode therein, said envelope having a neck, said main anodes being located in said neck, a base mounted on the neck of said envelope and encircling said main anodes 15 and extending above the upper edge of said anodes.

5. An alkali metal vapor lamp comprising an envelope, sodium, a plurality of main anodes, a starting anode and a thermionically active cathode 20 therein, said envelope having a reentrant stem, a plurality of leads carried by said stem, said electrodes being electrically connected to said leads, all of said main anodes surrounding said stem and a shielding means between said main 25 anodes and said stem.

6. An alkali metal vapor lamp comprising an envelope having a press, an alkali metal therein, a plurality of conductors sealed in said press, a thermionically active cathode secured to two of 30 said conductors, a plurality of electrically conductive supports secured to said other two conductors and extending therefrom, a main anode secured to each of said supports, all of said main anodes being located at that end of the envelope containing 35 the press, and discharge starting means located near said cathode.

7. An alkali metal vapor lamp comprising an envelope having a press, an alkali metal therein, four conductors sealed in said press, a thermionically active cathode connected to the two intermediate conductors, and a pair of main anodes electrically connected to the two end conductors, all of said main anodes in said envelope being 40 located at that end of the envelope containing 45 said press, and insulating means on said conductors to prevent discharge therebetween, and means forming a part of said lamp for initiating a discharge in said device.

8. An electric discharge device comprising an 50 envelope having a reentrant stem, an ionizable medium therein, a plurality of conductors carried by said stem, a thermionically active cathode secured to two of said conductors, inverted L-shaped conductors secured to two other of said conductors, main anodes surrounding said stem and secured to the long arms of said inverted L-shaped conductors, and insulating sleeves surrounding the major portion of all of said conductors, all of said main anodes surrounding said stem. 55

9. An alkali metal vapor lamp comprising an envelope, sodium, a plurality of main anodes, a starting anode and a thermionically active cathode 65 therein, said envelope having a reentrant stem, a plurality of leads carried by said stem, said electrodes being electrically connected to said leads, all of said main anodes surrounding said stem and a metallic shielding means located between 70 said main anodes and said stem, said shielding means being entirely supported by said stem.
